UNITED STATES PATENT OFFICE.

FRANCIS S. MONROE, OF OAKLAND, ASSIGNOR TO ISABEL M. SOMERS, OF SAN FRANCISCO, CALIFORNIA.

COMPOSITION FOR CLEANING TEXTILE FABRICS, WOODEN AND METALLIC SURFACES, &c.

SPECIFICATION forming part of Letters Patent No. 295,882, dated March 25, 1884.

Application filed June 18, 1883. Renewed January 25, 1884. (No specimens.)

To all whom it may concern:

Be it known that I, FRANCIS S. MONROE, a citizen of the United States, residing at Oakland, in the county of Alameda and State of California, have invented a new and useful 5 Composition of Matter or Compound for Cleansing Textile Fabrics, Wooden and Metallic Surfaces, &c., of which the following is a specification.

10 My composition consists of the following ingredients, combined in about the proportions stated, viz: nitrate of potash, one-fourth ounce; borax, one dram; French white castile-soap, one-half ounce; concentrated aqua-

15 ammonia, one ounce; distilled water, two quarts. The nitrate of potash and the borax are to be pulverized or ground into an im- palpable powder and mixed with the castile-soap, which has been first scraped or shaved

20 into fine shavings, and the shavings then rolled or broken between the hands. This mixture is then thrown into a vessel contain- ing distilled water and allowed to stand until dissolved, which usually occupies three or

25 four hours. When the borax, potash, and

soap have been thoroughly dissolved in the pure water, the aqua-ammonia is then added, and the whole is thoroughly mixed by agitation or stirring. The liquid is then drawn off into bottles for sale or future use.

In using the above-named composition, the article to be cleaned should be brushed free of all dust, and the cleansing compound is applied with a piece of soft sponge, rubbing hard. The article is then rinsed with clean 35 water and allowed to dry.

Having thus described my invention, what I claim, and desire to secure by Letters Patent, is—

The herein-described composition of matter, 40 to be used for cleansing textile fabrics, wooden and metallic surfaces, consisting of water, aqua-ammonia, white castile-soap, borax, and nitrate of potash, in the proportions specified.

In testimony that I claim the foregoing I 45 have hereunto set my hand and seal.

FRANCIS S. MONROE. [L. S.]
